POLE REINFORCEMENT

Michael Ruggieri, Stroudsburg, Pa., assignor to
 Line Material Company of Pennsylvania, East
 Stroudsburg, Pa., a corporation of Pennsylvania

Application January 14, 1939, Serial No. 250,969

6 Claims. (Cl. 20—99)

This invention relates to improvements in reinforcing means for wooden poles.

One object of this invention is to provide for weakened wooden poles, a metal pole reinforcement adapted to be driven into earth surrounding the pole and to compact the earth as the reinforcement reaches its final pole-reinforcing position, thereby to aid the pole reinforcement in its function.

As will hereafter be apparent, pole reinforcements are subjected to greater disruptive forces at the portion adjacent the surface of the ground about the poles than at portions of the reinforcements more remote from said surface. Therefore, it is an object of this invention to strengthen the pole reinforcement portion adjacent the surface of the ground and also by reason of this strengthened portion to cause compacting of the ground as previously noted.

More specifically, it is an object of this invention to provide an improved pole reinforcement with a longitudinally-extending rib which terminates in ribs diverging upwardly at the portion of the reinforcement adjacent the surface of the ground and adapted to compact the surface of the ground in lateral directions relative to the reinforcement about the base of the reinforced wooden pole during the installation of the reinforcement and also adapted to strengthen the reinforcement at said portion.

Another object is to provide a pole reinforcement which will, by reason of its ability to compact the earth about a pole, be urged toward the pole and held in contact therewith as it is forced to its final position of pole reinforcement.

In the drawing:

Fig. 1 shows a view in side elevation of the pole reinforcement embodying this invention.

Fig. 2 is a sectional view taken on the line 2—2 of Fig. 1.

Fig. 3 is a view in side elevation of a modified form of the pole reinforcement embodying this invention.

Fig. 4 is a sectional view taken on the line 4—4 of Fig. 3.

Like parts are designated by similar reference numerals throughout the several views.

Particular reference may now be had to Figs. 1 and 2 wherein E designates a section of earth in which the base portion of a wooden pole P is embedded. As indicated in Fig. 1, the portion R of the pole beneath the ground level of the earth E is weakened by deterioration. It is this portion of the pole for which the pole reinforcement M is provided as a strengthening member.

In order to strengthen the pole and prolong its service, the reinforcing member or reinforcement M is driven into the ground E adjacent the pole P and secured thereto above the ground level by means of a pair of clamping rods 6.

Preferably, the reinforcement M is cast in one

piece having its base or plate portion 8 curved transversely in horizontal section to conform substantially to the circumferential contour of the pole P. The upper end of the reinforcement is provided with a driving head 7 adapted to receive driving blows when the reinforcement member is being driven into the earth alongside of the pole.

The driving head is reinforced by a pair of ribs 10 which diverge downwardly from the lower portion of the driving head 7 and merge at their lower extremities into a pair of bracing ribs 12 extending along the sides of the upper portion of the reinforcement from the bolt-receiving ears 15 and 16 adjacent the ground level to the bolt-receiving ears 13 and 14 at the upper end of the reinforcement. The ears 13 and 14 are connected to the driving head 7 by means of ribs 17, thereby being reinforced against lateral stresses produced by the bolt 6 connected to the ears 13 and 14.

Ears 13 and 16 are provided with slots 18 to receive the headed ends 19 of the bracing rods 6 to facilitate connection of the rods with the ears, and ears 14 and 15 are provided with apertures 20, see Fig. 3, to receive the threaded end of the rods 6 and to prevent withdrawal of the rods while the nuts 26 are being drawn onto the threaded ends of the rods.

The lower portion 4 of the reinforcement M, which is disposed below the lower ears 15 and 16, is provided with a rib 21 located centrally of the portion 4 and terminating in a beveled edge 22 at the lower end of the portion 4. The upper end of the rib 21 merges into the upwardly diverging ribs 23 which extend to and terminate in the lower ears 15 and 16. Preferably, the lower end of the portion 4 of the reinforcement is beveled at 24 on each side to form a wedge-like end cooperating with the beveled edge 22 of the rib 21 to minimize resistance to forces driving the reinforcement into the earth.

It is also preferred that the lower portion of the reinforcement be inclined outwardly and upwardly at 25 relative to the base 8 and toward the margin of the rib 21 upon each side of the rib 21 to serve as a wedge cooperating with the ribs 23 for compacting the earth as the reinforcement reaches its final position during driving operations.

Installation of the reinforcement is accomplished by placing the curved base 8 in contact with the pole P and the lower end resting on the ground and then driving the reinforcement into the ground by repeated hammer blows on the driving head 7. As the reinforcement reaches the position shown in Fig. 1, the earth adjacent the ground level is wedged outwardly and laterally relative to the pole P, thus compacting the earth about the pole and imposing additional

resistance to displacement of the pole and the reinforcement.

When the reinforcement has been driven to its final position, it is then secured to the pole by means of bracing rods 6. The threaded ends of the rods 6 are inserted in the apertures 20 of the ears 14 and 15 and then bent around the pole allowing enough rod length so that the head ends may be placed in the slotted ears 13 and 16. The rod is then drawn snugly about the pole by tightening down the nuts 26 in an obvious manner.

From the foregoing, it will be obvious that the reinforcement M adds its strength to that of the deteriorated portion R and it has been found that under severe testing conditions which would tend to break the pole at the portion R, the pole actually breaks off at the stronger pole portion above the upper end of the reinforcement.

Additional means for securing the upper end of the reinforcement M may be provided in the form of three apertures 28 adapted to receive lag screws (not shown) or a bolt (not shown) extending through the pole.

Figs. 3 and 4 represent a modification of the reinforcement shown in Fig. 1. As will be seen from the application of the numerals, this reinforcement is substantially like that shown in Figs. 1 and 2, but the intermediate portion is provided with a transverse rib 27 connecting upwardly-diverging ribs 30 which merge into the lower ears 15 and 16. In turn, the rib 27 is reinforced by the triangular portion 33 which connects the ribs 30 below the rib 27 and connects the rib 27 with the point of juncture between the ribs 30 and rib 21. Thus the divergent ribs 30 are substantially reinforced in performing their function of adding strength to the intermediate portion of the reinforcement at ground level and of compacting ground that may be more solid than usual.

From the drawing and the foregoing description, it will be apparent that I have provided for poles having a weakened section, a novel reinforcement adapted to compact ground about the pole as it is driven into the earth, that is provided with a maximum reinforcing strength at ground level, that effectively adds its strength to that of a weakened pole section, that will be held in contact with a pole by means of compacted earth as the reinforcement is driven to its final position, and that is simple to manufacture and install.

I claim:

1. A pole reinforcement adapted to be driven into the ground alongside of a pole, said reinforcement comprising a member adapted to contact said pole longitudinally thereof and including a portion adapted to be set in the ground alongside said pole, said portion having on its exterior a rib extending from the lower end of said portion and terminating at its upper end in a pair of ribs diverging from the first-mentioned rib toward the upper end of said member and positioned at a point intermediate the ends of said reinforcement, each of said pair of ribs terminating in a reinforcing rib spaced from the other reinforcing rib, said reinforcing ribs terminating in a driving head flush with the upper end of said member, said pair of ribs being positioned relative to said portion to compact said ground as the reinforcement is driven thereto, and means for securing said reinforcement to said pole.

2. A pole reinforcement adapted to be driven into the ground alongside of a pole, said reinforcement comprising an elongated member, a reinforcing rib extending longitudinally of said member, said member intermediate its ends having a ground-compacting portion inclined outwardly toward the margin of said rib, thereby to wedge said reinforcement into supporting relation with said pole as the reinforcement is driven into the ground.

3. A pole reinforcement which is adapted to be driven into the ground alongside of a pole, said reinforcement comprising an elongated member, a reinforcing rib extending longitudinally of said member and terminating in a pair of divergent ribs intermediate the ends of said member, each of said pair of ribs terminating in a reinforcing rib spaced from the other reinforcing rib, said reinforcing ribs terminating in a driving head flush with the upper end of said member, said member having a ground-compacting portion inclined outwardly toward the margin of said divergent ribs, thereby to wedge said reinforcement into supporting relationship with said pole and to compact the surface area of the ground about said pole.

4. A pole reinforcement adapted to be driven into the ground alongside of a pole, said reinforcement comprising an elongated member having intermediate its ends a wedge-like portion integral therewith, said wedge-like portion diverging upwardly into a plurality of reinforcing ribs, said reinforcing ribs terminating in a driving head adjacent the upper end of said member, said wedge-like portion compacting the surface area of the ground adjacent said pole as the reinforcement is driven to its final position of pole reinforcement.

5. A pole reinforcement adapted to be driven into the ground alongside of a pole, said reinforcement comprising an elongated member having a lower portion provided with a longitudinally-extending rib terminating in a pair of spaced reinforcing ribs extending from the first-mentioned rib toward the upper end of said member, a cross rib connecting intermediate portions of said reinforcing ribs, and a ground compacting portion inclined outwardly from said member, thereby to wedge said reinforcement into supporting relation with said pole as the reinforcement is driven into the ground.

6. A pole reinforcement adapted to be driven into the ground alongside of a pole, said reinforcement comprising an arcuately curved base member, a longitudinally-extending rib which terminates in a pair of reinforcing relatively divergent ribs, each of said pair of ribs terminating in a reinforcing rib spaced from the other reinforcing rib, said reinforcing ribs terminating in a driving head, cross ribs normal to each other and connecting intermediate portions of said divergent ribs, said divergent ribs, cross ribs and longitudinally-extending rib being interconnected to form a triangular reinforcing portion, and a ground compacting portion inclined outwardly from said member adjacent said triangular portion and cooperating therewith to wedge said reinforcement into supporting relation with said pole as the reinforcement is driven into the ground.

MICHAEL RUGGIERI.
